[57] CLAIM

The ornamental design for a multi-function container,
as shown and described.

DESCRIPTION

FIG. 1 is a perspective view of a multi-function container showing my new design, with cap in a closed condition;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view;

FIG. 8 is a second perspective view of the multi-function container showing the cap opened;

FIG. 9 is a cross-sectional view of FIG. 8 taken along the section line 1—1;

FIG. 10 is a front view of FIG. 8;

FIG. 11 is a rear view of FIG. 8;

FIG. 12 is a top plan view of FIG. 8; and,

FIG. 13 is a side view of FIG. 8.
